UNITED STATES PATENT OFFICE

BERNARD FISCHLER, OF BROOKLYN, NEW YORK, ASSIGNOR, BY MESNE ASSIGNMENTS, TO THE COLUMBUS DENTAL MANUFACTURING CO., OF COLUMBUS, OHIO, A CORPORATION

PONTIC FOR BRIDGEWORK

Application filed December 17, 1924. Serial No. 756,511.

My invention relates to bridgework and more particularly to a bridgework for the bicuspids and molars.

The general object of my invention is to provide pontics of bridgework of a character that the porcelain or root of a bicuspid or molar may be replaced without disturbing the position of the bridgework in the mouth, so that the occlusal attachment or casting of the pontic, either bicuspid or molar, and the connection of the same with the abutments of the bridgework remain undisturbed, whereby to make provision for the replacing of the porcelain tooth-root of a pontic for the purpose of making the tooth-root or porcelain portion interchangeable, thus permitting substitution of a tooth-root of different size to suit changing conditions of the gum. A porcelain tooth-root of a pontic is often referred to in practical dentistry as the porcelain tooth-root facing but will hereinafter be referred to as the porcelain portion or root of the pontic in distinguishing it from the casting or occlusal attachment.

The nature of my invention and its distinguishing features and advantages will clearly appear as the description proceeds.

Reference is to be had to the accompanying drawings forming a part of this specification, it being understood that the drawings are merely illustrative of practical examples of the invention.

Figure 1 is a front elevation of upper teeth having a bridge therein the root of one of the pontics being omitted to clearly show the form of the casting at a pontic;

Figure 2 is a vertical section through the gum and pontic in a plane indicated by the line 2—2, Figure 1;

Figure 3 is a perspective view of the root or porcelain portion of the pontic;

Figure 4 is a perspective view of the casting of the pontic;

Figure 5 is a side elevation of a bicuspid illustrating a pontic of slightly modified form;

Figure 6 is a rear elevation or elevation at the lingual surface of the pontic shown in Figure 5;

Figure 7 is a vertical section of a pontic further modified;

Figure 8 is a rear elevation of the pontic shown in Figure 7.

In the illustrated example of my invention the letter *a* indicates a portion of the upper gum; *b*, a molar to which the bridge is attached; and *c* the bicuspid to which the bridge is attached.

In carrying out my invention the bridge includes the usual abutment casting 10 applied to the molar *b* and 11 indicates the abutment casting applied to the bicuspid *c*. The manner of securing the abutment castings 10 and 11 may be in accordance with any approved method as the abutments 10, 11 of the bridge form no part of my invention which relates to the pontics, that is to say, that bicuspid and molar between the molar *b* and bicuspid *c*.

The pontics in accordance with my invention include the root or porcelain 12 of the molar pontic and the casting, cap or occlusal attachment 13 of the molar pontic. The numeral 14 indicates the occlusal attachment or casting for the root or porcelain 15 of the bicuspid of the pontic of the bridgework.

The occlusal attachments 13 and 14 are substantially the same except as the shape varies to conform to the molar root 12 or bicuspid root 15, so that the same reference characters will apply to the distinctive features in each attachment 13 and 14. The molar root 12 and the bicuspid root 15 are formed at the morsal end of each root with cut-outs or entrant surfaces at opposite sides to form a dovetail 16 extending from the lingual side of the root forwardly and terminating short of the facial side of the root. Each side 17 of the cut-out of a pontic root inclined to form the side of the dovetail 16. The adjacent side 18 of the cut-out, however, in the form shown in Figures 1 to 4 is formed to present a flat incline. The formation of the side cut-outs leaves the morsal end 19 of the root of reduced width, said surface 19 being the morsal surface of the dovetail 16. The morsal surface 19 of the root 15 is opposed to the gingival surfaces 20 of the occlusal attachments 13, 14, which, it will be observed particularly from Figure 2 extend

obliquely and in a flat plane which declines from the lingual side or back of the occlusal attachment to the facial edge 21 of the attachment, said facial edge being formed by the convergent gingival surface 19 of the attachment and the morsal surface 22 of the attachment which morsal surface presents the cusps as usual, said morsal surface thus being generally in a horizontal plane except as the surface is varied by the form of the cusps or protuberant members 22 on the morsal surfaces for masticating. The numeral 23 indicates the side members on the occlusal attachments 13, 14, said side members mating the dovetail 16 and conforming to the inwardly directed side surfaces 17 and adjacent surfaces 18 of the cut-outs or entrant recesses produced in forming the dovetail 16. It will be seen that the slope of the opposed surfaces 19, 20 is downwardly and forwardly from the lingual side or back of the pontic. Hence, as will be particularly clear from Figure 2, the root 12 or the root 15 may be replaced by one of different size without disturbing the attachments 13, 14, it being understood that said attachments 13, 14, are as usual soldered to each other and to the abutments 10, 11. Thus, the occlusal attachment 13 or 14 presents in a generally horizontal plane the morsal surface 20 of the pontic and at the same time said surface presents at the gingival side a slope corresponding with the similar slope of the root 12 or 15, so disposed as to permit the sliding of the root 12 or 15 into place from the front rearwardly. When the root is in place on the occlusal attachment, it is held firmly by reason of the dovetail or undercut recesses in the root and the corresponding members 23 of the occlusal attachment.

It will be seen that the side flanges 23 which pertain to the form of occlusal attachment shown in Figures 1 to 4 presents an opening 24 at the lingual side, that is to say, the occlusal attachment is open at the back or lingual side.

In the form shown in Figures 5 and 6, the occlusal attachment 114 corresponds in all respects with the attachment 14 except that the upper edges 25 of the side members, 123, which correspond with the members 23, present a curved gingival line instead of a straight line 26, which straight line 26 conforms to the straight line or flat morsal surface 18 of the pontic root. The morsal surface 118 of root 115 is curved to correspond with the gingival surface 25 of the members 123. The numeral 116 indicates the dovetail of root 115 corresponding with similar dovetail 16 in Figures 1 to 3.

In Figures 7 and 8 the numeral 215 indicates a bicuspid root corresponding with the roots 15 and 115 and the numeral 214 indicates the occlusal attachment thereof. The root 215 presents a curved surface 218 corresponding with curved surface 118. The at-

tachment 214 is formed with a flange 223 which is continuous about the lingual side or back of the tooth. Thus, in the form shown in Figures 7 and 8, the flange 223 does not have an opening corresponding with the opening 24 in Figure 4 but is continuous about the sides and back of the root. The root 215 is undercut to correspond with the flanges 223. The gingival surface 220 in Figures 7 and 8 and the gingival surface 120 in Figures 5 and 6 are in an oblique plane as are the opposed surfaces 19, 20 in Figures 1 to 4. In all forms, therefore, the said flat oblique surfaces are produced presenting an incline from the facial toward the lingual side of the pontic. In all cases the casting or occlusal attachment 14, 114, 214 presents the greatest vertical thickness at the lingual side of the tooth and tapers toward the facial edge 21.

I would state in conclusion that while the illustrated examples constitute practical examples of my invention, I do not limit myself strictly to the exact details herein illustrated, since, manifestly, the same can be considerably varied without departure from the spirit of the invention as defined in the appended claims.

Having thus described my invention, I claim:

1. An artificial tooth having an integral root, and a flat oblique occlusally disposed end extending from the lingual to the labial face, and having undercut side walls, the undercuts increasing in depth toward the lingual face, a recess in the lingual face of the tooth intercepting said undercuts at their lingual end.
2. An artificial tooth having an integral root, and a flat oblique occlusally disposed end extending from the lingual to the labial face, and having undercut side walls, the undercuts increasing in depth toward the lingual face, a recess in the lingual face of the tooth intercepting said undercuts at their lingual end, and an occlusal attachment having undercut side flanges designed to engage the undercut walls of the tooth, and a flange at the lingual end of the flanges designed to engage the said recess in the lingual face of the tooth.
3. An artificial tooth having an integral root, a recess in its lingual face and a flat oblique occlusally disposed end extending from the lingual to the labial face, and having undercut side walls, the undercuts increasing in depth toward the lingual face, and an occlusal attachment having undercut side flanges designed to engage the undercut walls of the tooth, and a flange at the lingual end of the flanges designed to engage the said recess in the lingual face of the tooth.

BERNARD FISCHLER.
